W. P. WEBBER.
THERMAL CIRCUIT CLOSER.
APPLICATION FILED MAY 29, 1919.

1,343,803.

Patented June 15, 1920.

UNITED STATES PATENT OFFICE.

WILLIAM PINCKNEY WEBBER, OF BROOKLYN, NEW YORK.

THERMAL CIRCUIT-CLOSER.

1,343,803.

Specification of Letters Patent. Patented June 15, 1920.

Application filed May 29, 1919. Serial No. 300,527.

To all whom it may concern:

Be it known that I, WILLIAM P. WEBBER, a citizen of the United States, and a resident of the city of New York, borough of Brooklyn, in the county of Kings and State of New York, have invented a new and Improved Thermal Circuit-Closer, of which the following is a full, clear, and exact description.

10 This invention relates to an automatic heat controlled fire alarm device.

One of the general objects of this invention is to provide a device of simple and inexpensive construction, which when subjected to a predetermined temperature, will cause a suitable alarm circuit to be established to indicate the existence of fire or excessive heat.

More specifically, one of the objects of this invention is to provide a heat-controlled fire alarm device which may be conveniently held either in a vertical, horizontal or any intermediate position, such for example as on a ceiling or side wall, so that said device will be responsive to a predetermined increase of temperature either within a room or between the walls or ceiling and partitions, to cause an electric circuit to be completed.

30 A further object is to provide a heat-controlled fire alarm device having but few parts so constructed and arranged that they are inclosed, being thus protected from dirt and accidental injury, but are readily accessible for inspection or renewal of parts when required.

The above objects are accomplished by providing a casing adapted to be suitably positioned in a wall, ceiling or other desired place and having a relatively good heat-conducting material extending from each end of the casing so as to be subject to a change of temperature at these places. Within the casing there are members which are held in an elevated position against gravity by preferably a metal composition which will melt at a relatively low predetermined temperature, these members being so arranged that if there is excessive heat on either side of the wall, the metal composition will be melted, thus permitting the elevated member to move and complete an electric alarm circuit.

More specifically in the preferred construction, there is provided a metal casing open to the rear and having an insulated

metal cap at the front thereof, said part being preferably depressed to offer a greater exposed surface, the inner side of said cap being coated with a composition metal having a low melting point, there being further provided a ball, also coated with the composition metal, which is held in an elevated position on the inner surface of the cap. A metal cone also coated on its inner surface with the composition metal is inserted within the casing with the apex extending rearward of the casing, and the enlarged part or base of the cone surrounding but insulated from the depressed portion of the cap. A metal composition-covered ball is also held in the end of the cone on an inclined surface. Terminals are taken to an electric circuit from the cap and casing respectively so that if the temperature at either end of the device is high enough to melt the metal composition, the ball will descend, thus completing the alarm circuit between the cap and casing.

Other objects and advantages will be apparent from the following description and the accompanying drawings. Similar characters of reference designate like parts in the several views.

In the drawings showing one of the preferred forms of the invention—

Figure 1 is a sectional view of the invention taken on the line 1—1 of Fig. 2.

Fig. 2 is a side elevation view of the device positioned in a wall, shown in section.

Fig. 3 is a front elevation of Fig. 2.

Fig. 4 is a sectional view looking in the direction of the arrows and taken on the line 4—4 of Fig. 2.

Fig. 5 is a modification of the invention.

Fig. 6 is a perspective view of the cone.

In the drawings showing one of the preferred forms of this invention, the main body of the device comprises a metal casing 1 preferably cylindrical in form, open at the forward part thereof, the rear part being restricted and terminating in an open-ended tube. The restricted portion of the casing forms an annular ring or shoulder 4, which forms a suitable seat when the said casing is positioned on a wall, ceiling or other support 5. It is understood that, when so positioned, the tube 3 will extend through a suitable opening 6 in the wall or other support 5.

As a means of positioning the casing 1, there are provided, preferably integral

therewith, flanges 7 through which screws 8 or other suitable means may pass to position the casing. A projecting ear portion 9 of the casing serves as one terminal for an electric circuit to which a conductor 10 may be connected. A cone member 11, made preferably of metal, is positioned within the casing 1 and tube 3, the forward or base part of said cone being of substantially the same form as the forward end of the casing 1, the apex or rear end of said cone being cut away, and the taper of the cone being such that the apex end of said cone extends inwardly of the tube 3, the forward end 12 of the tube serving as a seat or support for the cone member.

It is to be noted that the cone is preferably made of a metal which is a relatively good conductor of heat, such as copper, and 20 is in contact with the casing 1 and tube 3, thus serving as an electric and heat conductor.

An insulator 13 of any suitable material is provided, which serves normally to hold 25 a cap 14, covering the forward part of the casing 1, out of electrical contact therewith. The insulator 13 has a shoulder 13' at the front thereof, which extends around the forward part of the casing and prevents the 30 cone or the casing from coming in contact with the cap 14. In order to afford a relatively large exposed surface, which will be subject to a change in temperature, the front of the cap is pressed inwardly forming substantially a hemisphere 15, but it is understood that any other suitable form may be used for this purpose.

There is provided for the cap 14 a projecting ear portion 16, which serves as a 40 terminal to which a conductor 17 may be fastened by any suitable means. It is thus seen that if the terminals of an electric circuit, comprising a source of current 18, an indicating or alarm device 19, is connected 45 by suitable conductors to the terminals 16 and 9 of the cap 14 and casing 1 respectively, the said circuit may be completed by an electrical connection between the terminals 16 and 9.

50 In the preferred form shown, there is provided a means to establish said circuit, said means being heat-controlled to automatically establish the circuit when a predetermined temperature is reached on either 55 side of the device, the preferred form herein comprising a metal ball 20, which is positioned at the smaller end of the cone preferably by having connected therewith by a suitable metal composition connection 25, 60 which will melt at a relatively low temperature, a rod 21 composed of a relatively good heat-conducting material, such as copper, which extends rearwardly of the cone and projects through the opening in the apex 65 thereof, the rod preferably having a twist

or turn 22 therein, which contacts with the open end of the cone and serves to hold the ball 20 in an elevated position. The said rod extends rearwardly of the partition 5 the desired distance so as to expose a relatively large surface and to be subject to an increase of temperature. It is thus seen that if the rod 21 is subject to relatively high temperature, the heat will be conducted through the rod 21 to the point at which it 75 is connected to the ball 20, and if the temperature is high enough, the composition holding the metal ball 20 in an elevated position will melt and permit the ball 20 to descend and complete the circuit through the 80 terminals 16 and 9 of the cap 14 and casing 1 respectively, thus automatically establishing the alarm circuit.

As an additional carrier of heat in order to make the device more sensitive, there is 85 provided at the rear end of the tube 3 another metal cylindrical tube 23 in contact with and extending in the said tube, there being connected with said tube 23 a coil of wire 24 preferably of copper, which extends 90 rearwardly, the said coil affording an increased surface which will be subject to an increase in temperature between the walls and will conduct the heat therefrom back to the casing 1 and assist in melting the composition metal connection 25 holding the ball in an elevated position when the proper temperature has been reached.

An opening 28 is provided in the front 15 of the cap 14, through which extends a metal 100 rod 26, one end of said rod extending through the cap and having connected thereto another ball 27 by the metal composition soldered connection 25, this connection being similar to the connection between the rod 21 105 and ball 20 at the smaller end of the cone. The ball 27 is held in an elevated position so that if the composition connection is melted, the ball 27 will descend and complete the electric circuit between the terminals. In 110 the preferred construction shown, a bar 29 is positioned across the forward portion of the cap and has an opening therein, through which extends the wire rod 26, the said bar merely functioning to hold the rod 26 in 115 proper position.

If desired, the inner surface of the cone, the inner surface of the front cap and the surface of the metal balls may be coated with a film 25' of composition metal or solder 120 having a relatively low melting point. One of the advantages in coating the above-mentioned surfaces with the composition metal or solder is that such surfaces are protected from oxidation and when they are subjected 125 to such a temperature as will cause them to melt, there will be exposed a bright un-oxidized surface which will form a relatively good electrical conductor. An additional advantage in having the parts positioned as 130

shown is that the melted metal will flow downward on the surface of the cone and assist in making an electrical contact between the cone 11, which is in electrical contact with the casing 1, and the cap 14. It is thus seen that if the temperature on either side of the partition or wall 5 is high enough, the heat will be conducted to either one of the balls 27 or 20 by the heat conductors 26 or 21 respectively and will cause the soldered connection to be melted, thus permitting the balls to descend and establish an alarm circuit.

It is to be noted that when the cap and cone surfaces have been coated with the composition metal or solder, which melts at a relatively low temperature, that as a relatively large surface of the respective parts is exposed, the film carried thereon will also melt, and even though the balls themselves did not descend, the melted solder or composition would descend to the lower corner of the device and establish the electric circuit between the cap and casing. It is to be understood that either one or both of the methods may be used.

In order to have the device function, it is only necessary to have enough of the composition metal or solder to hold the ball members in an elevated position.

There is shown in Fig. 5 a modified construction in which the tubes 3 and 23 and the wire coil 24 are eliminated. In such a construction, the heat is conducted to the ball members 27 and 20 respectively through the rod members 26 and 21 and the cap front 15 and cone 11 respectively.

It is thus seen there is herein provided a simple and compact construction which functions automatically upon increase of temperature to establish an alarm circuit when an excessive temperature exists upon either side of a partition member.

While but one preferred form of this invention has herein been shown, certain changes and modifications may be made without departing from the spirit and scope thereof.

Having thus described the invention, what I claim as new and desire to obtain by Letters Patent is:

1. In a device of the character described, a casing open at one end, a cap to cover said open end, an insulator between said cap and casing, a ball member, a connection between said ball member and said cap, said connection including a metal of relatively low melting point, which holds said ball in an elevated position and another ball member, and a cone, said ball member being held in an elevated position within the cone by a metal connection which melts at a relatively low temperature.

2. A thermal circuit closer, adapted to be positioned in a support to be responsive to

a temperature change on either side of said support, said device comprising a casing, a cap insulated in one end thereof and means within the casing normally held in an elevated position by a connection between said casing and said means, said connection including a metal composition having a relatively low melting point, whereby when the composition is melted the said means will gravitate downward and establish an electrical connection between said cap and said casing.

3. In a device of the character described, a metal cylindrical casing open at one end and having at the other end thereof a restricted portion forming an annular ring, a hollow metal cone having the base thereof in contact with the open end of said casing and the apex thereof extending through the restricted portion of said casing, a cap for the open end of said casing, an insulator between said casing and said cap, a ball within and spaced from said cone and a connection between said cap and said ball normally holding said ball in an elevated position, said connection including a metal composition having a relatively low melting point.

4. A thermal circuit closer comprising a cylindrical casing open at one end, a hollow metal cone having the base thereof in contact with said casing, a cap for said casing, an insulator between said casing and said cap, the front of said casing being hemispherical in shape and extending within the base of the cone member, a member spaced from said cone and connected with the hemispherical portion of said cap by a metal composition having a low melting point and another ball spaced from said cap and connected to said cone by a metal composition having a relatively low melting point.

5. A thermal circuit closer comprising a cylindrical casing open at one end, a hollow metal cone having the base thereof in contact with said casing, a cap for said casing, an insulator between said casing and said cap, the front of said casing being hemispherical in shape and extending within the base of the cone member, a member spaced from said cone and connected with the hemispherical portion of said cap by a metal composition having a low melting point, another ball spaced from said cap and connected to said cone by a metal composition having a relatively low melting point, a rod consisting of a relatively good heat conductor connected with said member spaced from the cone, said rod extending outwardly therefrom, and another rod consisting of a relatively good heat conductor connected with the other member spaced from said cap, said last-named rod extending outside of said cone.

6. In a device of the character described, a metal casing, a hollow cone adapted to be

positioned within said casing and to be in contact therewith, a cap for one end of said casing, said cap having a depressed portion, an insulator between said cap and said casing, the depressed portion of said cap being within said casing when positioned, a film coating for the inner surface of said cone, said coating consisting of a metal composition having a relatively low melting point, a similar coating for one side of the depressed portion of said cap, a ball spaced from said cone and connected with said cap by said composition metal and another ball spaced from said cap and connected to said cone by the metal composition coating on said cone.

7. A device of the character described comprising a casing, a member having an inclined surface, in contact with said casing, another member positioned adjacent said casing, an electric insulator between said members, a plurality of weighted members held in an elevated position, one of said members being connected to the inclined member by a fusible material and another weighted member being connected to the other member spaced from said inclined

member by a fusible material, said weighted members being arranged so that when the fusible material melts, either one of the 30 weighted members will descend and establish an electric circuit between the inclined member and the adjacent member spaced therefrom.

8. A thermal circuit closer adapted to be 35 responsive to a predetermined increase in temperature on either side of a support, said device comprising a casing, and a member having an inclined surface in electrical contact with said casing, a cap insulated from 40 said casing, and a plurality of members one of each being connected to the cap and inclined surface respectively by a metal composition having a relatively low melting point, and terminal connections with said 45 cap and casing respectively, whereby the said device may be held in one of two vertical positions or a horizontal position and upon melting of any one of the connections, the said member will by gravity descend 50 and establish an electrical circuit between the said terminals.

WILLIAM PINCKNEY WEBBER.
